(57) **CLAIM**

I claim the ornamental design for a bottle basket for a decanting cradle, as shown and described.

DESCRIPTION

FIG. 1 is a perspective top, rear and left side view of a bottle basket for a decanting cradle showing my new design;

FIG. 2 is a left side elevational view of a bottle basket for a decanting cradle, the right being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of a base for a decanting cradle in FIG. 1 is included for the purpose of illustrating environmental structure that forms no part of the claimed design.
